UNITED STATES PATENT OFFICE

PAYSON T. SYKES, OF AUBURN, MAINE.

DESIGN FOR A CIGAR OR CIGARETTE HOLDER.

SPECIFICATION forming part of Design No. 35,023, dated September 3, 1901.

Application filed August 5, 1901. Serial No. 70,836. Term of patent 14 years.

To all whom it may concern:

Be it known that I, PAYSON T. SYKES, a citizen of the United States, residing at Auburn, in the county of Androscoggin, State of Maine, have invented and produced a certain new and original Design for a Cigar or Cigarette Holder, of which the following is a specification.

In the accompanying drawings, Figure 1 is a plan view of a holder made in accordance with my design. Fig. 2 is a section through the same on the line 2 2 of Fig. 1, and Fig. 3 is a section through the holder on the line 3 3 of Fig. 2.

The design, as shown, consists of a tubular body circular in cross-section and open at both ends. This body comprises the elongated substantially cylindrical portion A, the shorter substantially cylindrical end portion B, connected thereto by an annular contracted portion or neck C, and the end portion D,

connected with the opposite end of the portion A by a flattened contracted portion or neck E, formed by two transverse depressions in the opposite sides of the holder, as shown. 25 Between said transverse depressions the wall of the holder projects slightly in laterally-opposite directions, as shown at F. The portion D is conical, tapering from its junction with the neck E to its outer end G, in which 30 is formed the opening H.

What I claim, and desire to secure by Letters Patent, is—

The design for a cigar or cigarette holder substantially as shown and described. 35

In testimony whereof I affix my signature in presence of two witnesses.

PAYSON T. SYKES.
